[57] CLAIM

The ornamental design for a counterfeit detection viewer apparatus for paper currency, as shown and described.

DESCRIPTION

FIG. 1 is a front perspective view of a counterfeit detection viewer for paper currency showing my new design;

FIG. 2 is a rear elevational view thereof;

FIG. 3 is a right side elevational view thereof, the opposite side is a mirror image;

FIG. 4 is a top plan view thereof;

FIG. 5 is a bottom plan view thereof;

FIG. 6 is a side perspective view of a second embodiment of a counterfeit detection view for paper currency showing my new design;

FIG. 7 is a perspective view of a third embodiment of a counterfeit detection view for paper currency showing my new design;

FIG. 8 is a bottom plan view of FIG. 6; and,

FIG. 9 is a bottom plan view of FIG. 7.
